BUTTON

Lues Reiter, Providence, R. I.

Application January 19, 1935, Serial No. 2,475

2 Claims. (Cl. 24—90)

This invention relates to buttons and particularly, to those intended to be covered with leather or the like and secured in place by means of a leather or the like loop.

5 My invention contemplates the provision of a button loop member so shaped and arranged in the button as to be dependably held therein against considerable stresses and strains and adapted to be easily and economically assembled with the remaining parts of the button.

10 My invention further contemplates the provision of a multiple piece button of the leather type provided with simple, inexpensive and efficient attaching means not likely to become detached from the button.

15 My invention further contemplates the provision of a button wherein the attaching means comprises a one-piece leather or the like loop provided with projecting shoulders or keys de-

20 signed to adequately and permanently maintain the loop in its proper operative position in the button.

25 The various objects of my invention will be clear from the description which follows and from the drawing, in which,

Fig. 1 is an elevational view of my improved button partly broken away to show the interior structure.

30 Fig. 2 is a perspective view, partly in section, of the same, showing the attaching loop in its operative position.

35 Fig. 3 is a similar view of the attaching loop as it appears before it is folded and doubled over.

Fig. 4 is a top plan view of the metal cup for holding the backing washer.

40 In the practical embodiment of my invention which I have shown by way of example, the backing disc or washer 10, which forms the back of the button, is preferably made of leather or similar material and is set into the inner metallic cup 11, which is made preferably of aluminum or similar light and comparatively rigid material. The bottom 12 of said cup is provided with a 45 central preferably square opening 13 surrounded by a wall 14 pressed up from part of the material removed from the bottom to form the opening 13, and of less height than that of the upstanding peripheral rim 15 of the cup, said rim being of 50 less height than that of the washer 10.

The washer 10 is provided with a central preferably round opening 16 of substantially the same, or slightly greater diameter than the length of one of the sides of the square wall 14, whereby 55 the edges of said wall cut slightly into the surface

17 surrounding the opening 16 and insure the attachment of the washer to the cup. It will be understood that the diameter of the rim 15 of the cup is such that the rim tightly receives the lower part of the washer to aid in holding the washer and cup together. After the washer 10 and the cup 11 have been assembled, a loop 18 of a single piece of leather or other suitable material of preferably uniform thickness is inserted through the openings 13 and 16. 10

As shown in Fig. 3, said loop is formed from a flat member having the elongated narrower portion 19 and the enlarged shouldered end portions 20. The end portions 20 are each approximately semi-circular in form and being wider than the 15 part 19, form the aligned shoulders as 21 extending beyond the edges of, and substantially perpendicular to the center line of the elongated portion 19.

The edges 22 and 23 of said elongated portion 20 converge toward the middle of said portion from each of the enlarged ends 20 so that at its central point as 24, the loop member is of the least width.

To insert the loop into its operative position in 25 the button, it is folded in half to form the integral bend 24 and to arrange the end parts 20 in registration, and the bend 24 is then passed through the square opening 13, through which it may be forced. It will be understood that the 30 loop when doubled, is substantially square in cross-section and of approximately the same size as that of the opening 13 in both directions. The tapering of the side edges of the loop part 19 makes it possible to insert the loop readily 35 through the opening 13 and through the washer opening 16.

After the parts 18, 10 and 11 have been thus assembled, a sheet of covering material as 25, of circular form and made preferably of leather 40 or the like material, is arranged about a second metal cup 26 having a convex bottom 27 and a cylindrical rim, a sheet 28 of padding material such as paper or the like being optionally interposed between the cup and the leather covering 45 to make the outer surface of the button softer. The cup 26 is arranged outwardly of and concentrically with the inner cup 11.

It will be understood that the cover 25 and the padding sheet 28 are of sufficient diameter 50 to permit the peripheral edges thereof to be turned over the peripheral edge 29 of the outer cup 26 and crimped thereto.

The assembled washer 10, cup 11 and loop 18 are set inside of the assembled cover 25, padding 55

28 and cup 27, the rim part 30 of the cup 26 being bent inwardly toward the washer to hold the parts securely together. The outer face 31 of the cover 25 may be suitably stamped or decorated with any desired design as 32, said cover being sufficiently compressible for that purpose when backed by the padding 28, and the bottom 21 of the cup 26 being sufficiently yielding to permit the design to be indented therein if desired.

15 It will be noted that the extreme edge 29 of the cup 26 is bent inwardly a sufficient distance to interpose the bent portions 33 of the cover and of the padding 28 into the path of the rim 15 of the cup 11 so that once assembled, the washer cannot without difficulty be removed from the button. It will further be seen that the shoulders 21 engaging as they do the bottom 12 of the cup 11, cannot be pulled through the holes 13 and 20 16, and form a secure locking arrangement for the loop. It will thus be seen that I have provided a simple button in which the parts including the loop are efficiently secured together and which is extremely difficult to disassemble.

Whilc I have spoken of the description of certain species of amphibia to you, I will now speak of the distribution of these animals in the different regions of the world. I will first speak of the Old World, and then of the New. I will then speak of the distribution of the different genera and species of amphibia in the different regions of the world.

I. Eleiairc:

ing its peripheral portion folded over the rim of said second cup and pressed between the peripheral edge of the washer and said rim, and a leather loop of a single piece of material of rectangular cross-section tapering in width from the ends thereof toward its middle and having enlarged shouldered ends of greater width than that of the square hole and that of the aperture of the washer, the shoulders of said ends being arranged between the faces of said cups and the tapered portion of the loop passing through and fitted into the square hole and passing through the aperture and thereby preventing turning of the loop in the button and securing the loop in place against detachment. 5 10

WHITE SREEMAN.
